Specification for Design.

Patented May 24, 1921.

Application filed November 20, 1920. Serial No. 425,581. Term of patent 7 years.

To all whom it may concern:

Be it known that I, MAURICE A. SMITH, a citizen of the United States, residing at Jeannette, county of Westmoreland, in the State of Pennsylvania, have invented a new, original, and ornamental Design for Glass Vessels, of which the following is a specification, reference being had to the accompanying drawing, forming a part thereof.

Figure 1 of the drawing is a side eleva-

tional view of a glass bowl showing my new design, and Fig. 2 is a bottom plan view of the same bowl.

I claim:

The ornamental design for a glass vessel, as shown.
